RELAXATION OSCILLATOR CAPACITANCE
MULTIVIBRATORHarland A. Bass, Mount Healthy, Ohio, assignor
to Avco Manufacturing Corporation, Cincinnati,
Ohio, a corporation of Delaware

Application August 1, 1947, Serial No. 765,362

2 Claims. (Cl. 250—36)

1

The present invention relates to relaxation oscillators or the like, and, while it has a wide range of prospective applications, it is of particular utility as employed in multivibrators of the type included in the electron beam-deflecting circuits of television receivers. Specifically, it relates to a novel cathode-coupled multivibrator for supplying control signals to the sweep generating circuits of a television receiver. The multivibrator is of the free-running type which is adapted to have its recurrence rate or frequency controlled by a unidirectional voltage, such as an automatic frequency control voltage. The invention resides generally in the provision of a feed-back network in such a multivibrator for reducing the susceptibility of the multivibrator circuit to noise, for minimizing undesired variations in the control voltage and for increasing the stability of the multivibrator.

In stating the problem which is solved by the present invention, reference is made to indirect synchronizing systems of the type commonly employed in television receivers. A typical superheterodyne television receiver of the superheterodyne type comprises a first detector or oscillator modulator, an intermediate frequency amplifier, a second detector for deriving the modulation components of the intermediate frequency carrier, and a synchronizing signal separator and filter for separating the horizontal synchronizing pulses and the vertical synchronizing pulses from each other and from the signal carrying the picture elements. The horizontal synchronizing pulses, for example, are applied to an automatic frequency control circuit, which compares their phase relationships to periodically recurring saw-tooth voltages produced by integration of voltages appearing in the horizontal beam-deflecting coil circuit of the television tube, in order to derive a resultant unidirectional control voltage. This control voltage is applied to a blocking oscillator and the output control signals of the blocking oscillator are in turn utilized for triggering a saw-tooth wave generating circuit. This last-mentioned saw-tooth wave circuit generates a current of recurring saw-tooth wave form in the horizontal beam-deflecting coils. The function of the A. F. C. circuit is to synchronize the saw-tooth current waves with the horizontal synchronizing pulses applied to the A. F. C. circuit from the output of the synchronizing signal separator and filter. The frequency of the oscillator output control signals and consequently the frequency of the saw-tooth current waves is functionally related to the magnitude of

2

the unidirectional control voltage appearing at the output of the automatic frequency control circuit. It has heretofore been considered necessary or highly desirable to provide an R.-C. filter combination between the output of the frequency control circuit and the input of the oscillator. Such a combination is represented by the elements 69, 70 appearing in Fig. 2 of U. S. Patent No. 2,358,545, issued September 19, 1944. 5 for example. The functions of this filter are to reduce the susceptibility of the oscillator circuit to noise, to minimize hunting and to smooth out abrupt or fast changes in the A. F. C. control voltage. The performance of this function has 10 heretofore been considered to require a relatively large capacitance of the order of one microfarad. It is desirable that there be provided a means 15 and method whereby this large capacitor may be dispensed with and a smaller capacitor utilized in lieu thereof.

In the radio manufacturing industry it is desirable that unnecessary circuit components be eliminated wherever possible and that essential circuit components which are capable of performing several functions be fully exploited. It 25 is, accordingly, an object of the present invention to provide an oscillator for the purpose set forth, said oscillator being adapted to be controlled by a direct current voltage, such as that derived from an automatic frequency control circuit, and at the same time to dispense with the above-mentioned large capacitor.

Another object of the invention is to provide a relaxation oscillator of the multivibrator type, 35 in which the heretofore unrealized potentialities of a multivibrator as a multiplier of capacitance are fully exploited, by providing a feed-back network between the anode and control electrode circuits of that one of the multivibrator tubes to which the control voltage is applied.

Briefly described, the invention comprises a 40 D. C. controlled multivibrator having a feed-back network and so arranged as to function also as a capacitance multiplier. For a better understanding of the present invention, together with other and further objects, capabilities and advantages thereof, reference is made to the accompanying drawing, in the single figure wherein there is symbolically represented a television beam-deflecting system of the indirect synchronizing signal type including an illustrative form 45 of capacitance-multiplying multivibrator in accordance with the invention.

Referring now specifically to Fig. 1, the elements thereof which are individually considered

to be prior art per se are shown in full-line block form. It will be understood that the synchronizing signal separator and filter unit 10 is appropriately coupled to an output circuit of a second detector included in a television receiver. For purposes of illustration only a horizontal beam-deflecting system is here shown. The synchronizing pulses from unit 10 may be applied to an automatic frequency control circuit 11. The direct current voltage output of unit 11 (i. e. the A. F. C. voltage) is applied to the input terminals A, B of an oscillator 12. The function of the oscillator is to generate saw-tooth voltage waves. These saw-tooth voltage waves are applied to a horizontal deflection amplifier 14 which produces saw-tooth current waves in the horizontal deflecting coils 15, 15 of the cathode ray television receiver tube 16. The output of amplifier 14 is coupled through an integrating network 17 back to an input circuit of the A. F. C. network 11. This integrating circuit 17 shapes the "kick back" voltage pulses applied to the deflecting coils 15, 15 into saw-tooth voltage waves. The last-mentioned saw-tooth voltage and the horizontal synchronizing pulses from unit 10 are applied to the automatic frequency control network 11 with such polarity and are therein so utilized that there is applied to the terminals A, B a unidirectional control voltage. This A. F. C. voltage is utilized to control the frequency of the control signal output of oscillator unit 12, to the end that the saw-tooth current waves appearing in coils 15, 15 may be properly phased with respect to the horizontal synchronizing signals originating at the transmitter and finally appearing at the output of unit 10. The system units so far specifically described correspond to those collectively shown in the prior art, with the exception that a cathode-coupled free-running multivibrator oscillator is here employed in lieu of the blocking oscillator generally employed. Accordingly, it is neither necessary nor desirable that such units be further described herein. Such units as 10, 11, 12, 14, 15, 16 and 17 are well known to those skilled in the art.

It has heretofore been considered necessary to provide a series R.-C. network including a very high capacitance on the order of one microfarad across the output circuit of unit 11 and between the output of A. F. C. circuit 11 and the input of oscillator 12, as mentioned above. The present invention, in one aspect, provides a means and method for eliminating this large condenser. Specifically, a multivibrator is employed in oscillator 12. It is recognized, of course, that a cathode-coupled multivibrator circuit is prior art, not only per se but also as used in sweep generation. The present invention, however, is premised in part on the novel directive concept and perception that a multivibrator has capacitance-multiplying potentialities which have heretofore not been realized, appreciated, or exploited. It is further recognized that other tube circuits have heretofore been employed as multipliers of capacity for other purposes. However, a circuit employing one tube section of a multivibrator as a multiplier of capacitance is believed to be novel. Accordingly, one improvement provided by the present invention resides in a feed-back network, generally indicated by the reference numeral 18, for intercoupling the anode and control electrode circuits of the first multivibrator tube 20.

Referring now to the multivibrator network, it comprises a pair of triode electronic vacuum tubes 20 and 21. The anode circuit of tube 21 is

coupled to the cathode-control electrode input circuit of tube 20 by a common cathode resistor 22. The anodes are connected to the high potential terminal (indicated as plus B) of an appropriate source of space current (not shown) by individual anode resistors 23 and 24. The anode circuit of tube 20 is coupled to the input circuit of tube 21 by an R.-C. network comprising a coupling capacitor 25 and a grid resistor 26, that terminal of the grid resistor remote from the grid of tube 21 being connected to the junction of the cathodes and resistor 22. Connected across the output of tube 21, specifically between its anode and ground, is a capacitor 27. This capacitor is periodically charged along a linear saw-tooth voltage characteristic and it periodically discharges through tube 21, thereby to generate the signals applied to the horizontal deflection amplifier 14.

Those portions of the multivibrator so far described, with the exception of the feed-back network presently to be described, are generally similar in construction, arrangement and operation to the sweep circuit multivibrator described in the article by J. L. Potter, page 713 et seq. of the proceedings of the Institute of Radio Engineers for June, 1938, vol. 26, No. 6, published by Institute of Radio Engineers, New York, New York.

In accordance with the invention a feed-back circuit comprising a resistor 28 and a capacitor 29 is connected between the anode and control electrode of the multivibrator tube 20. The A. F. C. voltage is applied to the input circuit of the same tube 20 to control the frequency of the saw-tooth signals.

In one successful commercial embodiment of the invention, employing separate sections of a 6SN7GT type tube for triodes 20 and 21, the following parameters were found satisfactory:

Element	Value
28	82,000 ohms.
29	0.1 microfarad.
25	82 micromicrofarads.
23	47,000 ohms.
45 24	1 megohm.
26	470,000 ohms.
22	1,000 ohms.
27	150 micromicrofarads.

It will be noted that a capacitance of 0.1 microfarad was found suitable for element 29. In prior art circuits a capacitance of the order of 1 microfarad was provided between terminals A and B, or between some equivalent points. In accordance with the invention, this large capacitor is dispensed with and the first tube section of the multivibrator is employed to perform an additional function as a multiplier of capacitance, whereby there is presented at the input terminals A, B an effective capacitance (equivalent to that formerly furnished by a 1 microfarad capacitor, for example) greatly in excess of the capacitance (element 29, 0.1 microfarad, for example) included in the feed-back network 18.

In operation, the effective capacitance appearing between the terminals A, B smooths out abrupt or rapid changes in the A. F. C. control voltage. As indicated, this high effective capacitance is obtained by connecting a capacitor of a radically lower value between the grid and plate of tube 20. The resistor 28 in series with the capacitor 29 is preferably included for the purpose of minimizing high frequency feed-back and aiding in the anticipation of sudden changes in the A. F. C. control voltage.

In operation, capacitor 27 is charged along a

linear voltage characteristic when tube 21 is non-conductive through a long time-constant circuit comprising ground, capacitor 27, anode resistor 24 and the space current source plus B. During the trace period, when capacitor 27 is being charged through its relatively long time-constant circuit, capacitor 25 will discharge the energy (placed therein during the retrace period) through its relatively long time-constant circuit comprising capacitor 25, resistor 26 and the cathode-anode circuit of tube 20, producing a current flow of such polarity in resistor 26 as to cut off current flow through tube 21. As the charge on condenser 25 decreases exponentially to the cut-off point of tube 21, that tube tends to and finally does become conductive. As tube 21 becomes conductive at the beginning of the retrace period condenser 27 discharges rapidly through a short time-constant circuit comprising elements 22 and 27 and the cathode-anode circuit of tube 21. At the initiation of the retrace period, since the plate current of tube 21 increases, the voltage across resistor 22 also abruptly increases whereby the positive bias applied to the cathode of tube 20 is increased. Tube 20 becomes less conductive and its plate voltage rises. By reason of the action of the R.-C. coupling network 25, 26, the voltage across capacitor 25 not being able to change instantaneously the potential applied to the grid of tube 21 abruptly becomes more positive and the conductivity of tube 21 is increased. The increase in the conductivity of tube 21 in turn increases the flow of current through resistor 22 and the bias on the cathode of tube 20. The cumulative effect of this regenerative action is such that the anode current in tube 20 is substantially decreased and tube 21 rendered conductive for a short interval of time. The anode current in tube 20 is reduced by the voltage developed across resistor 22 when the high plate current of tube 21 flows through it. During this retrace interval, grid current being drawn by tube 21 when the voltage across resistor 26 exceeds that across resistor 22, capacitor 25 is charged through a short time-constant circuit comprising ground, resistor 22, the cathode-grid circuit of tube 21, capacitor 25, resistor 23 and the space current source. Next tube 21 becomes less conductive as the grid of tube 21 approaches cathode potential and the current through resistor 22 decreases, whereby the bias on the cathode of tube 20 is decreased and the plate current in tube 20 tends to increase. The plate voltage of tube 20 falls and the cumulative action of the R.-C. network 25, 26 is such that the bias on the grid of tube 21 is increased until tube 21 is cut off, whereupon trace occurs and the cycle of events is repeated. The magnitude of the control voltage applied by unit 11 to tube 20 determines the length of each time interval during which tube 21 is cut off and therefore the frequency of the saw-tooth voltage output of unit 12. That is, during each cycle of operation tube 21 remains cut off as long as the voltage across resistor 26 is sufficient to prevent space current flow in this tube. Since the magnitude of the voltage across resistor 26 is determined by the plate current in tube 20 it is evi-

dent that the A. F. C. voltage will control the frequency of the multivibrator. When the bias in tube 20 is such that the plate current is low, the capacitor will initially be charged less, the cut-off level will be reached more quickly and the frequency of the multivibrator will increase. The oscillator including feed-back circuit 28, 29 functions degeneratively in multiplying capacitance in a manner analogous to the behavior of a feed-back circuit in an amplifier-type reactance tube circuit as pointed out in the last paragraph on page 214 and on page 215 of "Theory and Applications of Electronic Tubes" by Reich, 2nd edition, McGraw-Hill Book Company, New York, 1944.

While there has been shown and described what is at present considered to be the preferred form of capacitance-multiplying relaxation oscillator in accordance with the invention, it will be obvious to those skilled in the art that various modifications and substitutions of equivalents may be made therein without departing from the true scope of the invention, and it is accordingly intended in the appended claims to cover all such changes and variations as fall within the true scope of the invention and without the proper scope of the prior art. Such construction of the claims is desired as will best protect the true invention.

Having thus described my invention, I claim:

1. In an indirectly synchronized sweep-signal generating system for a television receiver, the combination of a source of unidirectional automatic frequency control voltage, a multivibrator comprising a pair of electron tubes of which one has a control grid-cathode input circuit, coupled to said source, and an anode circuit, and an inverse feedback network intercoupling said anode and said input circuit for providing an effective shunting capacitance across said input circuit, said capacitance being employed as a filter to steady the value of said automatic frequency control voltage, whereby to stabilize the output frequency of the generating system.

2. In an indirectly synchronized sweep-signal generating system for a television receiver, the combination of a source of unidirectional automatic frequency control voltage, a cathode-coupled multivibrator oscillator comprising a pair of electron tubes of which one has a control grid-cathode input circuit, coupled to said source, and an anode, and a resistance-capacitance network intercoupling said anode and said grid for providing an effective shunting capacitance across said input circuit, said capacitance being employed as a filter to steady the value of said automatic frequency voltage, whereby to stabilize the output frequency of the generating system.
